UNITED STATES PATENT OFFICE.

SAMUEL B. WILLIAMS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed June 27, 1924, Serial No. 722,631. Renewed April 5, 1926.

This invention relates to telephone systems, and more especially to systems of this character which utilize automatic switching equipment for the establishment of conversational connections.

In systems employing common controlling mechanisms located at the central office and serving to govern and control the selective operation of the automatic switches, it frequently happens that one of these mechanisms encounters trouble while in the exercise of its functions. The mechanism may become unable to proceed in its natural operation due to trouble which it may encounter at most any point between the time it is seized for use and the time when it completes its function of governing the switches. It is not desirable that a connection which has progressed successfully to a partial completion should be required to fail due to the fact that one of the controlling mechanisms becomes disabled after it is taken into use.

It is, therefore, the object of this invention to release a disabled controlling mechanism without defeating the connection which is undergoing extension and to thereupon take in use either the same or another mechanism for another trial.

A feature of the invention relates to a system in which a sender is connected to one of a number of markers for the purpose of controlling a selective switch together with means for disconnecting the marker from the sender if such marker fails to function, without disturbing the connection undergoing extension, and to connect said sender to any one of said markers for a retrial.

A further feature relates to means for preventing the sender from reconnecting to any marker which has encountered trouble and been released.

Referring to the drawing, Figs. 1 to 8, inclusive, when taken in the order illustrated in Fig. 9, disclose a portion of a telephone exchange system embodying the features of this invention.

Fig. 1 shows schematically a subscriber's line, a line switch, a trunk outgoing therefrom, a sender selector switch, and a portion of a subscriber's register sender.

Fig. 2 shows a district selector switch in which terminate the trunks leading from the line switches.

Fig. 3 shows a portion of one of a number of register senders.

Fig. 4 shows a multi-contact relay connecting device for associating the senders with the markers.

Figs. 5, 6 and 7 illustrate one of a number of controlling markers, the function of which is to determine the selective and testing operation of the selective switches such as the one shown in Fig. 2.

Fig. 8 shows a frame connector for connecting the markers to the frames of the switches shown in Fig. 2 and also a trunk connector for associating the marker with the different groups of trunks outgoing from the selector switches.

The system disclosed herein is an improvement upon the type of system illustrated and described in the patent of S. B. Williams, 1,517,331, Dec. 2, 1924, to which reference is hereby made for an understanding of the various operations which may hereinafter be referred to but not specifically described.

General description of the apparatus and operation.

The calling subscribers' lines, such as the line 100, terminate in vertical rows of contacts in coordinate line switches 101. These switches have access to groups of trunks, such as the trunk 102, which extend and appear in vertical rows of contacts in district selector switches. The trunk 102, for example, appears in the vertical row 201 of the selector 200. Another trunk 214 similarly occurs in the vertical row of contacts 202 and still other trunks may be provided.

The district selector switch 200 contains a number of vertical rows of contacts 203, 204, etc., in which appear numerical groups of trunks outgoing to succeeding switches.

The switches 101, 108, 200, etc., are of the coordinate type comprising a plurality of intermediate or horizontal links, together with vertical and horizontal selecting and operating bars and individual magnets for operating these bars. The district selector 200, for instance, has a number of links 205, 206, 207, 208, etc., with individual operating bars 215, 216, 217 and 218 and the respective horizontal operating magnets 219, 220, 221 and 222. Furthermore, the switch has vertical selecting bars 209, 223, 213, etc., together with corresponding operating magnets 210, 211 and 212.

The trunks 102 leading from the line switches to the district selector also appear

- in the sender selector switches 108. These selector switches have access to a number of recording senders, one of which is partially shown in Fig. 4 and in Fig. 1.
- 5 The register senders have an appearance in the sender connecting devices 400, each different sender being represented by a different multi-contact relay 403, 404, etc. The device 400 is also provided with a number 10 of relays 410, 412, etc., each of which represents a different one of the controlling markers. By operating the proper pair of these relays, any sender may be connected to any marker.
- 15 The marker includes a number of registers 500, 501 and 502 which receive the office portion of the entire designation, made up of three separate digits, from the register sender. Furthermore, a translating device 20 506 is comprised of a number of sets of multi-contact relays 510, 511, 512, etc., and 513, 514, 515, etc. and relays 507, 508 and 509. The registers cooperate with this 25 translating device in such a manner as to determine the selection of the group relays 612, 613, 614, 615, etc. These group relays determine the particular groups of trunks outgoing from the selector switches, which must be involved to route the call in the 30 direction corresponding to the designation transmitted to the sender.

The marker also determines the selection and operation of the proper one of the frame connectors 800 in order to associate 35 itself with the group of district frames 200 containing the frame in which appears the trunk over which the connection has been extended from the calling line. This frame connector 800 includes a number of relays 40 802 and 803, each individual to a different one of a plurality of markers. It also includes a number of multi-contact relays 804 and 805, each individual to a particular district frame 200 in the group. Relay 805, 45 for instance, is individual to the particular frame 200 shown in the drawing.

The trunk connector 801 comprises a 50 number of relays 810 and 811 each individual to a different marker. The connector 801, in addition includes a number of relays 812 and 813 each of which is individual to a different group of trunks outgoing from the district frames 200. The trunks of each group may be multiplied to appear in as 55 many selector switches as may be desired.

The marker is equipped with a testing device consisting of a number of sets of testing relays 700. These relays serve to test the horizontal links and the corresponding 60 outgoing trunks of any group.

Another function of the marker is to determine from the office code registration which it receives from a sender, the nature or class of the connection that is to be extended. This it does through the medium 65

of a translator 506 and may cause the operation of one of a number of class relays 528. These class relays, or the translator itself, may directly cause the closure of circuits extending back into the sender for the 70 operation of the proper class relays therein, thus giving the sender the necessary information to enable it to prepare to exercise the necessary control over the connection involved. 75

The line switch 101 and selector switches 200 and 108 may be of the general construction and operation as the one shown and described in the patent of C. L. Goodrum and J. N. Reynolds, No. 1,515,735, Nov. 18, 80 1924.

Detailed description of the establishment of a connection.

It will now be assumed for the purpose 85 of describing the invention, that the subscriber of line 100 wishes to obtain a connection extending through the district selector switch 200. The calling subscriber in initiating the call, causes the operation of 90 line switch 101 to extend his line over an idle trunk 102 to the district switch 200. The initiation of the call also causes the operation of sender selector switch 108 to 95 associate the trunk 102 with the idle register 100 sender shown in the drawing. During the operation of the sender selector switch 108, a circuit is completed for operating the relay 104. The relay 104 completes a holding circuit for the slow-release relay 106 which has been previously operated. This 100 holding circuit leads through the lower contact of relay 104 and the contact of relay 106. As soon as the sender selector switch 108 and the line switch 101 have 105 operated, the subscriber's line is included in series with the impulse relay 300 in the sender. The circuit for this purpose may be traced from battery, through the right winding of relay 300, outer right contact of relay 310, 110 thence through the sender selector switch 108, over the ring of the trunk 102, through the line switch 101, over the loop of the line 115 100, and returning through the line switch 101 and the sender selector 108, inner right contact of relay 310, to ground through the right winding of the balancing coil 303. Relay 300 operates and closes the circuit for the slow-release holding relay 301. Relay 301 completes operating circuits for the relays 302 and 316. These relays lock in circuits from battery, through their windings, thence through the inner right contact of relay 302, left contact of the relay 310, to ground at the inner left contact of relay 120 302. Relay 302 applies ground potential through its inner left contact, left back contact of relay 310, to the conductor 317 which serves to hold the sender selector switch 108 and the relay 104 in operated condition. 125

Recording the designation in the sender.—The subscriber now manipulates his dial (not shown) to transmit a number of impulses representing the wanted designation. The 5 impulse relay 300 responds to these impulses and cooperates with relays 305, 306, 307, 308 and 309 and with a set of counting relays diagrammatically illustrated by the rectangle 304, to cause the setting of a corresponding 10 number of registers illustrated diagrammatically by the rectangle 109. The general manner in which the foregoing operations may be accomplished is described and illustrated in the patent above mentioned to S. B. Williams, No. 1,517,331, Dec. 2, 1924.

Association of the sender with an idle marker.—As soon as the first three sets of registers 109 have been operated, a circuit is 20 closed extending over conductor 318, through the winding of relay 313, to battery. Relay 313 operates and causes the operation of relay 401 to initiate the actuation of the connector 400. The circuit for this purpose 25 may be traced from battery, through the lower contact of relay 402, left winding of relay 401, conductor 413, contact of relay 311, outer right back contact of relay 314, left contact of relay 313, conductor 320, conductor 321, to ground at the contact of relay 316. Relay 401 operates and closes a holding circuit from battery, through the winding of relay 402, right contact and winding of relay 401, to ground over the 35 circuit above traced. Relay 401 holds and relay 402 operates in this latter circuit. Relay 402 in operating, prevents the operation subsequently of another relay similar to the relay 401. With the relay 401 operated, 40 multi-contact relay 403 is energized in a circuit from battery, through its winding, left contact of relay 401, inner contact of relay 405, to ground at the inner lower contact of relay 402. Relay 403 locks through its 45 inner contact to ground at the upper contact of relay 402. Relay 402 completes a start circuit to select the first idle one of the markers. Assuming that the marker appearing in the multi-contact relay 412 is 50 busy, and that the next marker illustrated is idle, this start circuit leads from ground, through the inner lower contact of relay 402, lower contact of relay 405, left front contact of relay 406, left back contact of relay 407, left back contact of relay 408, left winding of relay 409, to battery at the outer contact of relay 411. Relay 409 operates 55 and closes a locking circuit from battery, through the winding of relay 411, inner right front contact and right winding of relay 409, conductor 414, to ground at the inner lower contact of relay 402. Relay 409 locks and relay 411 operates in this circuit. Relay 411 causes the operation of relay 408 60 in an obvious circuit to identify the asso-

ciated marker as busy. Moreover, relay 411 causes the operation of the multi-contact relay 410 in a circuit from battery, through the winding of the latter relay, middle right contact of relay 409, to ground at the inner contact of relay 411. With the relays 403 and 410 operated, the register sender is connected through the connecting device 400 to the marker shown in Figs. 5, 6 and 7.

As soon as the connector 400 operates, the 75 relay 600 in the marker is energized in a circuit from battery, through the winding of said relay, conductor 618, through the connector 400, to ground over conductor 413 as above traced. Relay 600 locks through its 80 inner right contact, outer right back contact of relay 607, outer right contact of relay 606, to ground at the inner left back contact of relay 602.

It will be assumed that the connection being extended is one involving a local line as a called line. Accordingly, the operation of relay 600 upon the seizure of the marker, causes the operation of the relay 711. The circuit for this purpose leads from battery, 90 through the winding of relay 711, inner right back contact of relay 710, conductor 622, inner right back contact of relay 606, to ground at the inner left contact of relay 600. 95

The record established on the registers 109 of the sender is now transferred to the corresponding registers 500, 501 and 502 of the marker. The registers 500, 501, and 502 are made up of the relays 516 to 527, inclusive, each register comprising four of these relays. The sender registers 109 are made up of corresponding relays which are operated in different combinations in response to the subscriber's dial. 105

It will be assumed that the designation is such that the third relay of the first register of the sender, the first and second relays of the second register, and the second relay of the third register of said sender, 110 are operated. Accordingly, the corresponding relays 518, 520, 521 and 525 of the marker registers 500, 501 and 502 are energized. The circuit for operating these relays extends from ground, through the inner left contact of relay 600, inner right back contact of relay 603, outer right contact of relay 608, left contact of relay 604, conductor 619, thence through the connector 400, conductor 111, thence through the 115 front contacts of the operated register relays 109 in the sender and returning through the connector 400 over conductors 416, 417, 418 and 419, through the windings of relays 518, 520, 521 and 525, respectively, to battery. The remaining register relays of the registers 500, 501 and 502 are also temporarily energized by means of a circuit which may be traced from grounded conductor 619, thence over conductor 530, through the nor- 120 125 130

mal contact of relay 504, right back contact of relay 503, conductor 415, through the connector 400, and thence through the back contacts of the register relays 109 which have failed to operate and returning through the connector 400 over the corresponding conductors to the windings of relays 516, 517, 519, 522, 523, 524, 526 and 527, to battery. When all the marker register relays have operated, a circuit is closed for operating relay 503, which may be traced from battery, through the winding thereof, thence in series through the contacts of the operated register relays to ground over conductor 530 as previously traced. Relay 503 locks through its inner right front contact and the normal contact of relay 504 to the grounded conductor 530. Relay 503 at its right back contact opens the operating circuits of the marker register relays which do not correspond to the operated relays in the sender, permitting these relays to release. The relay 503 also closes an obvious circuit for relay 504, which operates and locks through its own contact to the grounded conductor 530. Relay 504 in turn opens the holding circuit of relay 503, permitting this latter relay to release.

For an understanding of the manner in which the marker register relays are operated and released as above described, reference is made to the application of O. C. From, Serial No. 690,707, filed February 5, 1924.

Operation of the translator and selection of the proper trunk group.—The registers 500, 501 and 502 having been set, the translator 506 is now operated to prepare a circuit for selecting one of the group relays shown in the upper part of Fig. 6 to identify the proper group of trunks to be employed in extending the connection through the district selector switch 200. With the relay 518 of the register 500 operated, a circuit is closed for operating the relay 507, traceable from battery, through the winding of the latter relay, inner lower back contact of relay 519, inner lower front contact of relay 518, inner lower back contacts of relays 517 and 516, conductor 532, left contact of relay 504, to the grounded conductor 530. Since the register relay 525 is operated, a circuit is closed for operating multicontact relay 515 as follows: battery, through the winding of relay 515, inner lower front contact of relay 525, inner lower back contact of relay 524, to ground over conductor 532. Since the relays 520 and 521 of register 501 are operated, a circuit is completed for operating the multi-contact relay 512 and may be traced from battery, through the winding of the latter relay, through the distributing frame 533, contacts of relay 515, lower front contacts of relays 521 and 520, lower back contact of relay 523, to the grounded conductor 532. The group relay

612 is now operated in a circuit from battery, through the winding of this relay, distributing frame 620, conductor 621, through the distributing frame 534, contact of relay 512, lower contact of relay 507, conductor 70 535, to ground at the outer left contact of relay 608. Relay 612 represents the group of trunks appearing in the vertical row 204 of the district selector switch 200.

Operation of the district frame connector.—At the time relay 504 operates, it closes an energizing circuit for relay 807 of the frame connector 800. This circuit may be traced from battery, through the outer right contact of relay 604, conductor 623, winding 80 of relay 807 conductor 819, outer right contact of relay 504, conductor 540, through the connector 400, conductor 110, right back contact of relay 322, conductor 323, thence over conductor 111, through connector 400, 85 to ground over conductor 619 as previously traced. Relay 807 completes a circuit for relay 806 from battery, through the right winding of the latter relay, front contact of relay 807, back contact of relay 820, assuming this relay to be deenergized, upper contact of relay 809, to ground at the back contact of slow-release relay 808. When relay 806 is operated, it operates slow-release relay 808 in a circuit from battery, through the 90 winding of relay 808, lower back contact of relay 809, right contact of relay 806, conductor 821, outer left contact of relay 611, middle right contact of relay 607, outer right contact of relay 608, conductor 622, 95 inner right back contact of relay 606, to ground at the inner left contact of relay 600. The relay 808 operates and opens the operating circuit of relay 806. Relay 806 being slightly slow to release, however, 100 remains energized until relay 808 has fully operated. The holding circuit for relay 806 is then closed from battery, through the left contact of relay 806, left back contact of relay 823, winding of relay 809, to ground at 105 the front contact of relay 808. Relay 809 operates and opens the circuit of relay 808. Relay 808 releases and operates the multi-contact relay 802. The circuit for this purpose leads from battery, through the winding of relay 802, outer left contact of relay 806, upper front contact of relay 809, to ground at the back contact of relay 808. Relay 809 being operated, prevents the operation of another of the relays 806 and 823, 110 thereby avoiding interference by other markers. After relay 808 releases, relays 806 and 809 remain operated in a circuit which leads through the lower front contact of relay 809, right contact of relay 806, to 115 the grounded conductor 821.

The vertical operating magnet 210 controlling the row of contacts 201 in the switch 200, in which appears trunk 102, is now operated. The circuit may be traced from bat- 120

tery, through the winding of said magnet, conductor 227, left back contact of relay 107, through the switch 108, conductor 112, connector 400, conductor 421, normal contact 5 of relay 603, inner left back contact of relay 610, conductor 627 through contacts of the frame connector 800, to the grounded conductor 821. The magnet 210 rotates the vertical bar 209 and prepares all contacts in 10 the row 201. Magnet 210 extends the grounded conductor 227 through its inner lower contact, over conductor 228, through the winding of the multi-contact relay 805, to battery. Relay 805, which is individual to 15 the switch 200, operates and results in the connection of the conductors from the markers through to the frame of the selector switch 200.

With the frame connector 800 operated, 20 relay 603 in the marker is energized in a circuit from battery, through the winding of said relay, outer left back contact of relay 610, conductor 630, through the connector 800, to the grounded conductor 821. Relay 25 603 at its normal contact opens the circuit of magnet 210, but before this occurs said relay closes a substitute holding circuit for said magnet and also for relay 805. The holding circuits may be traced from battery, 30 through the winding and contact of magnet 210, conductor 228, and in parallel from battery, through the winding and contact of relay 805, contact of relay 802, conductor 824, make contact of relay 603, inner left 35 back contact of relay 610, to ground over conductor 627 as previously traced.

The vertical magnet 210 operates the horizontal magnet 226 which rotates the associated bar and prepares the special horizontal link 224. The relay 107 in the trunk 102 40 is now operated in a circuit from battery, through its winding, conductor 113, through contacts of the link 224, conductor 229, through the connector 800, conductor 826, 45 conductor 825, left contact of relay 603, to ground at the left back contact of relay 608. Relay 107 operates and at its left back contact opens the original energizing circuit of magnet 210.

50 *Operation of the district trunk connector.*— During the foregoing operations, the district trunk connector 801 is also being operated for the purpose of connecting the test relays 700 with the proper group of trunks outgoing 55 from the district selector 200. For starting the trunk connector 801 in operation, the relay 815 is energized in a circuit from battery, through the winding of said relay, conductor 827, through the distributing frame 620, outer left contact of group relay 612, conductor 628, middle left contact of relay 806, to ground at the back contact of relay 808. Relay 815 operates the relay 814 60 in a circuit from battery, through the left winding of relay 814, front contact of relay 65

815, back contact of relay 828, upper back contact of relay 817, to ground at the back contact of slow-release relay 816. Relay 814 when operated, causes the operation of relay 816 in a circuit from battery, through the 70 winding of the latter relay, lower back contact of relay 817, left contact of relay 814, to the grounded conductor 821. Relay 816 operates and opens the energizing circuit of relay 814. Relay 814 being slightly slow to 75 release, however, retains its armatures until relay 816 fully operates, at which time a locking circuit is closed as follows: battery, through the right winding and contact of relay 814, inner right back contact of relay 829, winding of relay 817, to ground at the lower front contact of relay 816. Relay 817 operates in this circuit and opens the circuit of relay 816, which subsequently releases. After relay 816 releases, the relays 85 814 and 817 are held energized in a circuit leading through the lower front contact of relay 817, left contact of relay 814, to the grounded conductor 821. The multi-contact relay 810 is now operated in a circuit from 90 battery, through its winding, outer right contact of relay 814, upper front contact of relay 817, to ground at the back contact of relay 816. The multi-contact relay 812, which is individual to the group of trunks 95 appearing in the vertical row 204 of the district selector 200, is operated in a circuit from battery, through its winding, conductor 830, contact of relay 612, conductor 631, middle right contact of relay 814, to ground 100 at the back contact of relay 816.

Testing links and trunks at the district selector switch.—The marker is now prepared to proceed with a test of the selected group of trunks outgoing from the district selector 200 and also the corresponding horizontal links. The right windings of the double wound test relays 701, 702, 703, etc., serve to test the trunks 230, 231, 232, etc., in order. The left windings of these relays 110 serve to test the corresponding horizontal links 205, 206, 207, etc. The test circuit for the trunk 230 may be traced from battery, through the right winding of relay 701, next to the inner back contact of relay 708, right 115 back contact of relay 706, conductor 714, through the trunk connector 801, conductor 831, to the sleeve conductor of the trunk 230. The test circuit for the corresponding link 205 may be traced from battery, through the 120 left winding of relay 701, inner back contact of relay 708, conductor 715, through the frame connector 800, conductor 236, to the test connector of the link 205. In a similar manner the test circuits for the remaining 125 trunks of the group and of the corresponding links may be traced through the windings of the test relays 800.

It will be assumed that the trunk 232 is 130 the first trunk in the group which is idle

simultaneously with the idle condition of its associated link 207. Since each of the preceding trunks or each of the corresponding preceding horizontal links is busy, or both 5 trunk and link are busy in each instance, the corresponding test relays 701, 702, etc., are operated either by the energization of one or of both windings. Since, however, the trunk 232 and its associated link 207 are 10 both idle, the test relay 703 remains deenergized. The operated relays 701 and 702 lock in circuits through their right windings and contacts, conductor 717, inner right contact of relay 608, to the grounded conductor 15 622.

At the instant the testing operation commences, a circuit is completed for operating the vertical magnet 212 of the district selector 200. This magnet requires an appreciable interval in which to become fully 20 operated and consequently serves to measure the time in which the relays 800 are required to test the links and trunks and to assume their operated and non-operated conditions accordingly. The circuit for magnet 212 may be traced from battery, through the winding thereof, conductor 237, through the connector 800, conductor 832, contact of relay 612, conductor 629, through the trunk 30 connector 801 to the grounded conductor 821. When magnet 212 is operated, it causes the energization of relay 604 in a circuit from battery, through the winding of relay 604, normal contact of said relay, conductor 632, through the frame connector 800, conductor 238, to ground at the contact of magnet 212. The relay 604 locks through its inner right contact and the inner left contact of relay 608 to the grounded conductor 35 622.

The relays 708 and 709 are now operated in circuits from battery, through their windings, thence over conductor 718, inner right contact of relay 604, to ground over conductor 45 717 as above traced. Relays 708 and 709 disconnect the test relays 700 to prevent their subsequent operation. The relay 728 relating to the idle trunk 232 and link 207 is now operated in a circuit from battery, 50 through the winding of relay 712, winding of relay 728, left back contact of test relay 703, left front contacts of preceding energized test relays 702, 701, etc., conductor 721, through the trunk connector 801, conductor 55 834, normal contacts of relay 605, contact of relay 607, thence to ground over conductor 718 as previously traced. Relay 712 also operated in this circuit.

Relay 712 operates the relay 314 in the 60 sender in a circuit from battery, through the winding of relay 314, conductor 324, connector 400, conductor 420, conductor 636, inner right contact of relay 711, to ground at the contact of relay 712. Relay 314 locks 65 through its left contact to the grounded

conductor 320. Relay 314 at its outer right back contact opens the original operating circuit of the relay 600. Relay 600, however, remains energized in the locking circuit previously traced.

The horizontal magnet 221 is next operated by means of a circuit from battery, through the right winding of said magnet, conductor 239, connector 800, conductor 835, middle left contact of relay 728, to ground over conductor 717. Another circuit for magnet 221 may be traced from battery, through both windings thereof, thence over conductor 234, through the connector 800, conductor 836, next to the outer front contact of relay 708, inner left contact of relay 728, to the grounded conductor 717. The closure of this latter circuit also results in placing a ground potential upon the test conductor of the horizontal link 207. Magnet 221 rotates the bar 217 and effects connection from the trunk 102 through the link 207 to the selected idle trunk 232.

Returning to the point where relay 604 operates, it may be noted that this relay 90 causes the release of the translator and marker register relays. Relay 604 at its left contact removed ground potential from conductor 619, causing the release of relay 504 and consequently the release of relays 507, 95 512 and 515. Relay 604 at its back contact opens the circuit of relay 807. When the translator releases, the group relay 612 is deenergized.

Release of the district frame and trunk connectors and of the marker.—The marker has completed its function in operating switch 200 and should now be released in order that it may be taken into use in connection with other calls. At the time the 105 district selector switch 200 operates to extend the trunk 102 through to the trunk 232, a circuit is closed for operating the release relay 607. This circuit may be traced from battery, through the winding of said 110 relay, conductor 635, right front contact of relay 728, conductor 730, conductor 731, through the trunk connector 801, conductor 840, thence through the district selector switch 200, sleeve conductor 115 of the trunk 115 102, to ground at the contact of slow-release relay 106. Relay 607 locks through its inner right contact, inner right contact of the relay 608, to the grounded conductor 622.

It may be noted at this time that the horizontal operating magnet 221 is also locked in a circuit from battery, through both its windings, thence through contacts of the switch 200, to the grounded sleeve conductor 115. Therefore, this magnet will remain operated after the marker, which furnishes the operating circuit therefor, becomes released.

Relay 607 opens the holding circuit of relay 600 and this latter relay becomes released. Relay 600 removes ground potential 130

from conductor 717, causing the release of all operated test relays. Relay 607 in operating, removes ground potential from conductor 821 causing the release of the frame 5 connector 800, trunk connector 801 and all operated relays associated therewith. The vertical magnets 210 and 212 are also released and the connection through the switch 200 is now held by the continued operation 10 of the horizontal magnet 221. Relays 603 and 604 are also deenergized.

At the time the relay 314 is operated in the sender, the original holding circuit of the relay 401 associated with the connector 400 15 is released. The relay 401, however, remains operated in a circuit which may be traced over conductor 413, conductor 116, thence through the connector 400, conductor 618, inner right contact of relay 600, outer 20 right back contact of relay 607, right back contact of relay 606, to ground at the inner left contact of relay 602. When relay 607 subsequently operates as just explained, the holding circuit of relays 402 and 401 is also 25 opened. These relays release, in turn causing the release of the connector 400 and all energized relays associated therewith. Thus the marker has been completely released and 30 disassociated from the selector switch 200 and from the sender.

Release of the sender.—From this point on, the connection may proceed in any suitable manner according to the class of the call concerned. After the sender has completed 35 its function, a circuit may be completed for the release relay 310. Relay 310 opens the holding circuit of the impulse relay 300 which releases the slow relay 301. Relay 301 in turn releases the holding relays 40 302 and 316. These relays move ground potential from the holding conductors to permit the release of the various energized relays in the sender.

The sender in releasing, also causes the 45 release of the sender selector switch 108 and the relay 104, whereby the subscriber's line is completed through to the repeating coil. The manner in which the release of the sender takes place is explained in the 50 above mentioned patent of S. B. Williams, 1,517,331, Dec. 2, 1924.

The marker encounters trouble.—If at any 55 time following the seizure of the marker for the purpose of controlling the extension of a connection the marker encounters trouble, as for instance the failure of a relay to operate or for any other reason, the marker will cease its normal progress with the result that the selector switch cannot be operated. To prevent the connection which has been successfully extended to a partial completion from failing on account of such an occurrence, it is desirable to discharge 60 the marker which has thus become disabled and to immediately seize either the same or

any other marker without releasing the extended connection. The trouble may be due to nothing more than a poor contact on one of the relays in the marker, which, if the marker were again employed, would not reoccur. Therefore, it may be desirable to give the same marker another chance, providing the sender happens to select such marker, rather than excluding it entirely from service. If, however, it is desired to exclude the 75 marker from service when it encounters trouble to avoid the danger of continued failures, this may also be done.

To accomplish these desirable ends, the 80 system is so arranged that if the marker encounters trouble after its seizure and a given interval of time, normally sufficient to permit the complete operation of the marker, expires, said marker will be immediately 85 discharged. After the discharge of the disabled marker, the sender immediately 90 seizes a marker, which may be either the same or a new marker according to the busy and idle condition of all markers available. After the re-seizure of another marker, a 95 new attempt is made to operate the switch to extend the connection.

At the instant the marker is seized, the relay 600 operates as previously explained. As soon thereafter as the constantly operating interrupter 637 completes its upper contact, the relay 601 operates as follows: 100 battery, through the winding of relay 601, normal contact of said relay, outer left contact of relay 600, to ground at the upper contact of interrupter 637. Following the closure of the upper contact of the interrupter, an interval of time expires before the closure 105 of the lower contact which is sufficient to permit the marker, if acting normally, to complete the exercise of its function. If, however, the marker finds trouble and refuses to proceed, the interrupter 637 on finally closing its lower contact causes the operation 110 of time measuring relay 602. The circuit may be traced from battery, through the winding of said relay, right contact of relay 601, to ground at the lower contact of interrupter 637. Relay 602 closes an obvious circuit for the lamp 638, which illuminates to notify the attendant that the marker 115 is in trouble. The relay 602, which is slow to release, temporarily locks in a circuit from battery, through its winding and inner right contact, normal contact of key 639, to ground at the outer right contact of relay 600. Relay 602 at its inner left back contact opens the locking circuit of the relay 600. Relay 600, however, still remains energized under control of the sender. Relay 602 furthermore, causes the operation of relay 311 in the sender by means of a circuit from battery, through the winding of said relay, conductor 325, connector 400, conductor 422, outer right contact of relay 602,

115

120

125

130

to ground at the outer right contact of relay 600. Slow-release relay 311 operates and severs the operating circuit of relay 600. Relay 600 thereupon releases and brings about the 5 release of the marker from the sender in the manner hereinbefore described. Relay 600 also opens the circuit of relay 602. All relays in the marker which have been operated, are released. Also the frame connector and 10 trunk connectors 800 and 801 are restored to normal, provided their operation has been either started or completed.

Since the key 639 is in its normal position as shown in the drawing, the marker will 15 immediately be restored to common use and may again be seized either by the sender shown or by other senders, as though no trouble had happened.

As soon following the discharge of the 20 marker as the slow relay 311 releases, the circuit hereinbefore traced is again completed for relay 600, and the connecting device 400 is actuated to re-associate the sender with the first idle marker. The first idle 25 marker may happen to be the same one which was previously used or it may be any of the other markers. Following the association of the sender with the marker, the record on the 30 registers 109 is transferred to the marker registers, the translator is operated, and the operations hereinbefore described proceed in a second attempt to control the district selector switch 200 to extend the trunk 102. If 35 no trouble is encountered by the marker at this time, the connection proceeds and the switch 200 is successfully operated. However, if trouble is again encountered for one reason or another and the time measuring 40 device in the marker counts a predetermined interval then the marker is discharged and another attempt is made.

This procedure will continue until the 45 sender has succeeded in associating itself with a marker which is capable of fully completing its functions.

If the attendant notes that any particular marker is showing signs of trouble frequently, he may throw the key 639 to its actuated position. The result of throwing the key 50 639 is to so modify the circuits of the marker that when the marker is subsequently discharged on account of trouble condition, it will be indefinitely held out of service and cannot be selected by a sender. Recalling 55 the point in the operation where the relay 602 actuates at the end of the time interval, it will be noted that this relay now locks permanently to ground through the key 639. Relay 602 in its operated condition, closes 60 a holding circuit for the relay 408 associated with the connector 400. This latter circuit may be traced from battery, through the right winding of relay 408, conductor 424, to ground at the outer left contact of 65 relay 602. The relay 408 renders the marker

non-selectable by extending the start wire through to the next relay beyond corresponding to the next marker in order.

After the marker has been investigated and the cause of the trouble remedied, it 70 may be restored to service by releasing the key 639.

What is claimed is:

1. In a telephone system, a selective switch, means for extending a connection to 75 said switch, a controlling mechanism, means for seizing said mechanism for use, said mechanism arranged to progress through a sequence of operations for governing the selective operation of said switch to further 80 extend said connection, means for releasing said mechanism if it fails to function normally without releasing said connection, and means for causing the reseizure of said mechanism in a repeated attempt to govern the 85 operation of said switch.

2. In a telephone system, a selective switch, means for extending a talking connection to said switch, a controlling mechanism, means for seizing said mechanism, 90 means for connecting said mechanism to the switch, said mechanism arranged to progress through a sequence of operations for controlling the selective operation of said switch to further extend the connection, means for disconnecting said mechanism from the switch and for rendering the mechanism available for reseizure if it fails to function 95 normally without releasing said connection, and means for causing the reseizure of said mechanism immediately in a second attempt 100 to control the operation of said switch.

3. In a telephone system, a selective switch, means for extending a connection to 105 said switch, a register sender, a controlling mechanism, means for connecting said sender to said mechanism, means in said sender for variably setting said mechanism, said mechanism arranged to control the selective operation of said switch to further 110 extend said connection, means for releasing said mechanism from the sender when such mechanism fails to function normally without disturbing the extended connection, and means for causing said sender to reseize said 115 mechanism in a further attempt to control the selective operation of said switch.

4. In a telephone system, a selective switch, means for extending a connection to 120 said switch, a marker for controlling the selective operation of said switch, means for seizing said marker for use, a time measuring device for releasing said marker if it fails to function properly after its seizure without disturbing the extended connection, 125 and means for causing the reseizure of said marker in a further attempt to control the operation of said switch to further extend said connection.

5. In a telephone system, an automatic 130

- switch, means for extending a connection thereto, a marker for selectively controlling the operation of said switch to further extend the connection, means for seizing said marker, for use, a time measuring device for counting a definite interval following the seizure of the marker, said interval being sufficient to allow the marker, if functioning normally, to control said switch, means effective at the end of the interval when the marker encounters trouble for releasing said marker without disturbing the extended connection, and means for causing the reseizure of said marker in a further attempt to control the operation of said switch.
6. In a telephone system, a selective switch, means for extending a connection thereto, a plurality of markers each arranged to selectively control the operation of said switch, means for seizing one of said markers for use, means for releasing the seized marker if it fails to function normally without releasing the extended connection, and means for thereupon causing the seizure of any one of said markers in a further attempt to control the operation of said switch.
7. In a telephone system, a selective switch, means for extending a connection to said switch, a plurality of markers each arranged to selectively operate said switch to further extend said connection, means for seizing an idle one of said markers for use, in a time measuring device for releasing the seized marker if such marker fails to function normally without disturbing the extended connection, and means for causing the reseizure of any one of said markers in a repeated attempt to govern the operation of such switch.
8. In a telephone system, an automatic switch, means for extending a connection thereto, a number of register senders, a plurality of markers each arranged to control the selective operation of said switch to further extend the connection, means for connecting one of said senders to an idle one of said markers, means controlled by the sender for setting the marker, means for releasing the connected marker if it fails to progress normally in its operation, and means for thereupon connecting the sender to any one of said markers, depending upon the busy or idle condition of such marker, in a repeated attempt to control the operation of said switch.
9. In a telephone system, a selective switch, a plurality of markers each arranged to selectively operate said switch, means for seizing the first idle marker for use, means for releasing the seized marker if it fails to function normally, means for rendering the released marker non-selectable, and means for thereupon seizing an idle one of the remaining markers in a repeated attempt to operate said switch.
10. In a telephone system, a selective switch, a plurality of markers each arranged to selectively control the operation of said switch, means for seizing an idle one of said markers for use, means for releasing the seized marker if it fails to progress normally with its functions, means for thereupon seizing one of said markers in a repeated attempt to control the operation of said switch, and manual means for determining whether a marker which has been released on account of trouble shall be withheld from service or may again be seized.
11. In a telephone system, a selective switch, means for extending a connection to said switch, a controlling mechanism, means for taking said mechanism into use, said mechanism arranged to govern the selective operation of said switch to further extend said connection, means for releasing said mechanism without releasing said connection, and means for again taking said mechanism into use in a repeated attempt to govern the operation of said switch.
12. In a telephone system, a selective switch, means for extending a connection to said switch, a plurality of controlling mechanisms each arranged to selectively operate said switch, means for seizing an idle one of said mechanism for use, means for releasing the seized mechanism without releasing said connection, and means for again seizing one of said mechanisms in a repeated attempt to selectively operate said switch.
- In witness whereof, I hereunto subscribe my name this 24th day of June A. D., 1924.

SAMUEL B. WILLIAMS.
